UNITED STATES PATENT OFFICE

JULIUS DORNETH, OF BERLIN-KONRADSHOHE, GERMANY, ASSIGNOR TO THE FIRM
TYPOGRAPH-GESELLSCHAFT M. B. H., OF BERLIN, GERMANY

MATRIX-SETTING AND TYPE-LINE-CASTING MACHINE

Application filed June 4, 1929, Serial No. 368,237, and in Germany November 29, 1928.

This invention relates to a matrix setting and type-line casting machine in which the matrices are guided in a cycle on wires and in which the line set is brought by means of a carriage to the casting point, and after the casting operation is moved away from it in order to be distributed. In such machines it has been impossible hitherto to use ring spacers which, as is well known, ensure good justifying, as the ring spacers were mounted on fixed square spindles. The invention makes it possible to use ring spacers by arranging them so that they are guided on guide wires in a manner known in itself, and by arranging the square spindles in an adjustable manner so that after the setting of the line in the casting place and after the casting operation, the said square spindles can be withdrawn from the spacer rings. A construction according to the invention with two square spindles arranged one above the other, is illustrated by way of example in the accompanying drawing in which:

Figure 1 is a plan of the casting place with the locking jaw closed, after the casting has been made.

Figure 2 is a plan with the line locking jaw open;

Figure 3 is a partial view, looking in the direction of the arrow I in Figures 1 and 2.

Figure 4 is an elevation, partly in section, looking in the direction of the arrow II in Figure 1.

Figure 5 is a section on line 5—5 of Figure 2.

Figures 6 and 7 are elevations, looking in the direction of the arrow III in Figures 1 and 2, with the parts in two positions.

Figures 8 and 9 are partial views looking in the direction of the arrow IV in Figure 6, with two positions of the parts, and

Figures 10 and 11 are detail views in section on lines 10—10 of Figure 6, in two positions.

The type-line which is made up in the usual manner from matrices 1 suspended on wires, and from ring spacers 2, each two of which are arranged one above the other (Figure 5) on a rod suspended from a wire 30 in the same way as the matrices, is pushed

for instance in the known manner by a slide from the setting point in a carriage movable in the vertical direction, to the casting point (Figure 2), cast in the carriage and then carried away by the carriage to distribute 55 the line again. At the casting point (Figure 2), the line is clamped fast between the jaws 3, 4. One jaw 4 is fixed, but arranged adjustably and may be locked in a guide 5 by means of a screw 6, a scale 7 ensuring 60 an exact adjustment. The other jaw 3 is mounted on a longitudinally adjustable spindle 8 which has a limited amount of rotation and is mounted in the machine bed.

To the spindle 8 is rigidly secured a sleeve 9 with a recess 10 at the top and with a lateral pin 11 with an end 12 bent upwards (see also Figures 8 and 9). Next to the sleeve 9 a vertical plate 13 is arranged forming part of the machine bed and provided with a slot 14 extending obliquely downwards and with a recess 15 on the upper edge. On the said plate is mounted in a longitudinally adjustable manner a second plate 17 guided by pins and slots 16 and provided with an arm 18 which is mounted in the recess 15 of the plate 13 and engages with the recess 10 of the sleeve. 70

An arm 20 (Figure 6) is connected by a link 19 to the plate 17 and the arm is secured to a vertical sleeve 21 which is rotatably mounted 80 on a pin 22 and provided at the top with a second arm 23 corresponding to the arm 20. The arms 20, 23 are provided at their ends with bores 24 which form bearings for one end of the square spindles 25 carrying the ring spacers 2, as will be more fully described 85 hereinafter.

When the spindle 8 is moved, by hand or by the machine in opposition to the pressure of a spring 26, in the direction of the arrow V (Figures 2 and 6), the sleeve 9 will drive the plate 17 by means of the arm 18, and this plate will turn by means of the link 19 the arms 20, 23 about the pin 22, from the position shown in Figure 2 into the position shown in Figure 1, whereupon the reduced ends of the square spindles 25 will engage with the bores 24 of the arms 20, 23, so that the latter will form bearings for the square spindles 25. 95

During the longitudinal movement of the 100

spindle 8, the pin 11 of the sleeve 9 will slide into the oblique guide 14, owing to which the spindle 8 will be turned simultaneously with its longitudinal movement, until the bent end 12 of the pin 11 is caught by a pawl 27, whereby the spindle 8 will be locked in that position (Figure 7).

The pin 11, 12 then strikes an arm 28 which is secured to a slide 29 guided in a guide 30. This slide has a rectangular recess 31 (Figures 10 and 11) through which a vertical rod 32 is guided with play. On the slide 29 against which presses a spring 34, is mounted a pin 33 which can engage with a hole of the rod 32. Owing to the movement of the slide 29 to the right, due to the striking of the pin 11, 12 against the arm 28, the pin 33 will be withdrawn from the rod 32, the latter will thus be released and pulled downwards by a spring 35, owing to which the drive for the machine parts effecting the casting of the line, will be thrown into action.

When the casting is finished, the parts must be brought back to their initial position. To that end, on the spindle 36 of the casting mould support (Figure 8) is provided a projection 37 which, on the turning of the spindle, strikes a projection or finger 38 of the rod 32 and raises the latter. A projection 39 provided on the rod 32 then strikes the pawl 27 and raises it, thereby releasing the pin 11, 12. The spindle 8 is then pressed back by the spring 26, and at the same time turned back by the oblique slot 14 so that it is again in the position shown in Figure 2. In the raised position of the rod 32, the pin 33 springs forward again and locks the said rod.

As the ring spacers 2 are suspended to wires like the matrices 1, are brought by a slide to the casting point and are moved away again from the latter by a vertically adjustable carriage, it is necessary that the square spindles 25 which produce the turning of the spacer rings and therefore the justifying of the line, should be moved out of the way before the cast line is moved to the point of distribution.

This is done according to the invention by a longitudinal movement of the square spindles 25. On an adjustable rod 40 (see also Figures 3 and 4) one arm of a bell crank lever 41 rests, the other arm of which presses against a horizontally guided rod 42. The latter meshes by means of teeth 43 with a toothed wheel 44, to the spindle 45 of which is secured a rocker arm 46. The latter is connected by a link to a sleeve 47 which is horizontally guided on a guide rod 48 and rigidly secured to one end of the square spindles 25. After the casting operation, the square spindles 25 are horizontally moved from the position shown in Figure 2 to the position shown in Figure 1, by means of the parts 40—48, during which time they are guided, in addi-

tion to the sleeve 47, also in the machine bed and in their driving wheels.

The spacer rings are therefore released and may be raised to the distributing point, whilst after the distribution of the matrices and of the spacer rings, the parts 25, 47, 46 etc. move in the opposite direction, the rod 40 is lowered and a spring 49 (Figure 3) turns the rocker arm 46 back again towards the machine bed.

On the rod 40 is provided a projection 50 which engages with a projection 51 of a vertically adjustable plate 52 (Figure 4). The latter is provided at its upper end with a pin 53 which engages from below with a lever 54. The latter is rigidly secured to a spindle 55 rotatably mounted in the machine bed, on the other end of which is mounted a similar lever 56. In the machine bed is further mounted a spindle 57 on which is mounted in an oscillating manner the bar 58 intended for the adjusting or levelling of the matrices, which is so constructed that owing to the weight distribution, it assumes the oblique position indicated in Figure 4.

To the rocking lever 46 is connected by a jointed rod 59 and a bell-crank lever 60, a horizontally adjustable bar 61, the end of which is bevelled. As soon as during the lowering of the rod 40, the rocking lever 46 is turned by the spring 49 towards the machine bed, it will press the bar 61 against a cam surface of the straightening or levelling bar 58 and thereby move the latter from the position shown in Figure 4 into that shown in Figure 5. At the same time the plate 52 will descend and allow the levers 54, 56 to engage behind the lugs 62 of the straightening bar, owing to which the latter will be locked. When the rod 40 is raised, the plate 52 will also be raised, owing to which the levers 54, 56 will be raised and as the bar 61 is at the same time pulled back, the straightening or levelling bar 58 will be released and will be able to turn upwards again.

As indicated in dotted lines in Figure 4, the rod 40 can be turned out of engagement with the bell crank lever 41, owing to which it will be released at the same time from the projection 51. Owing to this, the machine can work without the parts described being moved. The line can then be cast repeatedly.

The working of the machine is therefore as follows:

After the line has been set and brought by the carriage to the casting point (Figure 2), it must be justified. This is done by moving the spindle 8 in the direction of the arrow V (Figure 2). The plate 17 is thereby moved horizontally, and the arms 20, 23 are turned towards the line so that they are at right angles to the same. During the movement of the spindle 8, the latter is at the time turned by the cam slot 14 until the pin 12 is locked by the hook 27. At the end of this turning

movement, the pin 12 will move the slide 29 and release the locking device 33, so that the spring 35 will be able to pull down the rod 32 and to throw the machine into gear.

5 After the casting is finished, the spindle 36 of the casting mould holder will raise the rod 32 which, at the end of its movement, will be locked by the pin 33. During the raising of the rod 32, the locking device 27 will be released, and the spindle 8 moved back and turned by the spring 26, owing to which the plate 17 will be withdrawn and the arms 20, 23 turned outwards. At the same time, the rod 40 will also be raised by a cam of the 10 main shaft of the machine. The parts 54, 61 will be brought thereby to the distributing position so that the levelling bar can turn upwards whilst at the same time the square spindles 25 are withdrawn from the 15 spacer rings. The carriage can now carry the cast line upwards. During this operation which is performed by the machine, the cam which raised the rod 40, releases the same and allows it to fall down. The spring 49 then 20 pulls the rocking lever 46 towards the machine bed, since the back pressure on the bell-crank lever 41 has ceased, and by means of the gear wheel 44, brings the rack 43, the rod 42 and the bell crank lever 41 back to the 25 initial position.

Having now particularly described and ascertained the nature of the said invention and in what manner the same is to be performed, I declare that what I claim is:—

35 1. In a matrix-setting and type-line casting machine of the type having a frame, matrices, ring spacers, wires guiding said matrices and ring spacers, means to set the matrices, and ring spacers to a line, and means to bring the set line to the casting point and, after the casting operation, to move away therefrom, a square spindle for the ring spacers and means to withdraw the square spindle from the ring spacers after the casting of the line.

40 2. In a matrix-setting and type-line casting machine of the type having a frame, matrices, ring spacers, wires guiding said matrices and ring spacers, means to set the matrices and ring spacers to a line, and means to bring the set line to the casting point and, after the casting operation, to move away therefrom, a square spindle for the ring spacers mounted at one end in the frame, a bearing holding the other end of the square spindle, means to move away the bearing from the square spindle and means to withdraw the square spindle from the ring spacers after the casting of the line.

45 3. In a matrix-setting and type-line casting machine of the type having a frame, matrices, ring spacers, wires guiding said matrices and ring spacers, means to set the matrices and ring spacers to a line, and means to bring the set line to the casting point and,

after the casting operation, to move away therefrom, a square spindle for the ring spacers and a rocking lever engaging with one end of the square spindle, a rod moved during the working of the machine and transmission members and levers between said rod and said rocking lever.

5 4. In a matrix-setting and type-line casting machine of the type having a frame, matrices, ring spacers, wires guiding said matrices and ring spacers, means to set the matrices, and ring spacers to a line, and means to bring the set line to the casting point and, after the casting operation, to move away therefrom, a square spindle for the ring spacers and means to withdraw the square spindle from the ring spacers after the casting of the line, a bar adjusting the matrices in their vertical position and means to rock said bar out of its working position.

10 5. In a matrix-setting and type-line casting machine of the type having a frame, matrices, ring spacers, wires guiding said matrices and ring spacers, means to set the matrices, and ring spacers to a line, and means to bring the set line to the casting point and, after the casting operation, to move away therefrom, a square spindle for the ring spacers and means to withdraw the square spindle from the ring spacers after the casting of the line, a rod moved during the working of the machine, a bar adjusting the matrices in their vertical position, a second bar moved by the said rod and pressing against a cam face of the adjusting bar and turning it into its working position, whilst it is turned out of the said position by the acting of its own weight.

15 6. In a matrix-setting and type-line casting machine of the type having a frame, matrices, ring spacers, wires guiding said matrices and ring spacers, means to set the matrices, and ring spacers to a line, and means to bring the set line to the casting point and, after the casting operation, to move away therefrom, a square spindle for the ring spacers and means to withdraw the square spindle from the ring spacers after the casting of the line, a rod moved during the working of the machine, a bar adjusting the matrices in their vertical position, and locking levers which lock the adjusting bar in the working position and are thrown in and out by the movement of the said rod.

20 7. In a matrix-setting and type-line casting machine of the type having a frame, matrices, ring spacers, wires guiding said matrices and ring spacers, means to set the matrices, and ring spacers to a line, and means to bring the set line to the casting point and, after the casting operation, to move away therefrom, a square spindle for the ring spacers and means to withdraw the square spindle from the ring spacers after the casting of the line, a longitudinally movable spindle with a limited amount of rotation, a

line clamping jaw on said spindle, a plate moved by said spindle, and a rocking lever, connected by links to said plate and forming a bearing for the one end of the square spindle.

5 8. In a matrix-setting and type-line casting machine of the type having a frame, matrices, ring spacers, wires guiding said matrices and ring spacers, means to set the matrices, and ring spacers to a line, and means to bring the set line to the casting point and, after the casting operation, to move away therefrom, a square spindle for the ring spacers and means to withdraw the square spindle from the ring spacers after the casting of the line, a longitudinally movable spindle with a limited amount of rotation, a line clamping jaw and a pin on said spindle, a fixed oblique slot guiding the pin and turning the spindle and a locking device which prevents the machine from being thrown into gear and which is released by said pin.

9. In a matrix-setting and type-line casting machine of the type having a frame, matrices, ring spacers, wires guiding said matrices and ring spacers, means to set the matrices, and ring spacers to a line, and means to bring the set line to the casting point and, after the casting operation, to move away therefrom, a square spindle for the ring spacers and means to withdraw the square spindle from the ring spacers after the casting of the line, a longitudinally movable spindle with a limited amount of rotation, a line clamping jaw and a pin on said spindle, a fixed oblique slot guiding the pin and turning the spindle, a locking device for said pin when the machine is thrown into gear and automatical means for releasing the said locking device after the casting.

40 In testimony whereof I affix my signature.
JULIUS DORNETH.
